Patented Dec. 17, 1912.

UNITED STATES PATENT OFFICE.

CHARLES A. KOERNER, OF LOUISVILLE, KENTUCKY.

TO WHOM IT MAY CONCERN:

SUPPORT FOR CONCRETE REINFORCEMENTS.

INVENTOR'S PATENT

1,047,655.

Specification of Letters Patent.

Patented Dec. 17, 1912.

Application filed February 19, 1912. Serial No. 678,478.

To all whom it may concern:

Be it known that I, CHARLES A. KOERNER, a citizen of the United States, and a resident of Louisville, in the county of Jefferson and State of Kentucky, have invented a new and Improved Support for Concrete Reinforcements, of which the following is a full, clear, and exact description.

This invention relates to improvements in supports for the steel or other reinforcements for concrete, and has for an object to provide an improved structure which will correctly support the reinforcing members without defacing the finished work.

15 A further object of the invention is to provide an improved support for holding concrete reinforcements substantially centrally of the wall or other article being cast, and to bind together the various cross members of the support.

In carrying out the objects of the invention, any desired kind of reinforcements may be used, as for instance steel cables. These can be arranged to extend at right angles to each other, diagonally, or in any other desired manner. At each crossing a support is positioned which will hold the reinforcing members above or away from the bottom of the form and will also tie the reinforcing members together, a pair of interlocking extensions being provided for this purpose.

A practical embodiment of the invention is represented in the accompanying drawings forming a part of this specification, in which similar characters of reference indicate corresponding parts in all the views.

Figure 1 is a view showing a plurality of reinforcing bars with supports embodying the invention being applied thereto, the supports being shown inverted; Fig. 2 is a longitudinal vertical section through a slab showing supports embodying the invention arranged therein, the bottom of the slab being supported by a base member; Fig. 3 is a longitudinal vertical section through a support embodying the invention, the same being shown on an enlarged scale and having associated therewith a pair of bars extend-

ing at right angles to each other; Fig. 4 is a perspective view of a blank from which the support is formed; Fig. 5 is a plan view of a blank showing a slightly modified form of the invention; Fig. 6 is a perspective view of a still further slightly modified form of the invention; and Fig. 7 is a perspective view of a further modified form of holder.

Referring to the accompanying drawings by numerals, 1 indicates reinforcing bars crossing each other, and 2 the support as a whole. The support 2 is provided with a body portion 3 designed to have the sides 4 and 5 thereof turned down for acting as supporting legs, as clearly shown in Fig. 2. Extending from the body 3 are projections 6 and 7. The projection 7 is formed with ears 9 and 10 designed to be pressed over the projection 8 when the projection 8 is moved to the position shown in Fig. 3 for tying the reinforcing bars 1 together. It will be noted that the sides 4 and 5 are cut away at 11 and 12 for forming points or retaining feet 13.

In Fig. 5 will be seen a slightly modified form of the support 2, in which projections 14 and 15 are provided comprising merely extending tongues which are designed to be bent over the bars 1 and overlapped for tying, to a limited extent, the bars together.

In Fig. 6 a support 2 is disclosed in which the projection 7' is formed with a single extension 10' designed to be folded over the tongue 8'.

In Fig. 7 the holder 2 is shown formed with extensions 7'' having an enlargement 16 provided with a slot 17 in which the projection or tongue 8'' is fitted so as to properly tie together the reinforcing bars 1.

Having thus described my invention, I claim as new and desire to secure by Letters Patent:

1. A concrete reinforcement supporting blank comprising a body portion having substantially radiating feet, a pair of radiating tongues, and an interlocking member extending from one of said tongues.

2. In a concrete reinforcement support, a body portion; a plurality of legs extending at an angle from the center of said body

portion, each of said legs diverging and extending in a different direction, a pair of tongues extending from opposite sides of said body portion, said tongues being adapted to be bent over said concrete reinforcement, and means arranged on one of said tongues for locking the other of said tongues.

In testimony whereof I have signed my name to this specification in the presence of two subscribing witnesses.

CHARLES A. KOERNER.
